US00D632111S

(12) **United States Design Patent**
MacDonald et al.

(10) **Patent No.:** US D632,111 S
(45) **Date of Patent:** ** Feb. 8, 2011

(54) **DISPENSER**

(75) Inventors: **John W. R. MacDonald**, Bristol (GB);
Christopher L. Padain, Montvale, NJ (US); **Thomas E. Walker**, Bristol (GB);
Craig I. Wightman, Bristol (GB)

(73) Assignee: **Reckitt & Colman (Overseas) Limited** (GB)

(**) Term: **14 Years**

(21) Appl. No.: **29/314,991**

(22) Filed: **May 15, 2009**

(30) **Foreign Application Priority Data**

Nov. 20, 2008 (EM) 001042675-0001
Nov. 20, 2008 (EM) 001042675-0002

(57) **CLAIM**

The ornamental design for a dispenser, as shown and
described.

DESCRIPTION

FIG. 1 is a top, front, and rights side perspective view of a
Dispenser showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken-line disclosure in the views is understood to
represent portions of the article in which the design is embod-
ied, but which forms no part of the claimed design.

1 Claim, 2 Drawing Sheets
